UNITED STATES PATENT OFFICE.

ALBERT ROSENBAUM, OF NEW YORK, N. Y.

SELF-SETTING TIME-PIECE.

SPECIFICATION forming part of Letters Patent No. 389,111, dated September 4, 1888.

Application filed July 5, 1888. Serial No. 279,085. (Model.)

To all whom it may concern:

Be it known that I, ALBERT ROSENBAUM, of the city, county, and State of New York, have invented certain new and useful Improvements in Self-Setting Time-Pieces, of which the following is a specification.

The object of this invention is to provide an improved self-setting time-piece, which is intended to set the hands automatically by the action of the striking mechanism once in every twelve or twenty-four hours; and the invention consists of a self-setting time-piece in which a lever fulcrumed to the frame of the time-piece engages at one end a heart-cam on the arbor of the minute-hand, said arbor carrying a friction-tight driving-pinion, while the other end of said lever is engaged by an actuator connected to the striking mechanism, said heart-cam being axially adjusted on its arbor by a set-screw and by a graduated disk or segment relatively to a fixed index or pointer on the frame of the clock.

In the accompanying drawings, Figure 1 represents a rear elevation of a clock-movement with my improved self-setting time-piece. Fig. 2 is a horizontal section on the line xx , Fig. 1. Fig. 3 is a detail rear view of the self-setting attachment, shown as detached from the clock-movement; and Fig. 4 is a detail view of the graduated segment on the sleeve of the heart-cam, drawn on a larger scale.

Similar letters of reference indicate corresponding parts.

In the drawings, A represents the frame of a clock-movement of any approved construction, and B the transmitting main wheel of the striking mechanism. To the arbor C of the minute-hand is applied a heart-cam, D, by means of the sleeve d and set-screw d' , (shown in Fig. 2,) said sleeve carrying, preferably, back of the heart-cam D a graduated segment, E, by means of which the heart-cam D may be readily adjusted axially on the arbor C to one side or the other of a fixed index or pointer, e, of the frame A, as shown in Fig. 1. A lever, F, is fulcrumed to the frame A, one end engaging the heart-cam D, while the other end is bent around the transmitting main wheel B of the striking mechanism into the path of a pin, f , on the same, which pin on the striking mechanism serves as the actuator for the

fulcrumed lever F. The pin f engages the lever F once in every twenty-four hours, and preferably when the striking mechanism strikes twelve o'clock, as at that time the distance through which the main wheel B travels is greatest, so that the motion of the pin f imparts to the lever F a stroke of corresponding length. The pin f engages the lever F immediately before the clock strikes twelve, and releases the same as soon as it has struck twelve, so as not to interfere with or block the regular motion of the clock-movement. By the action of the pin f on one end of the lever F the opposite end of the same engages the heart-cam D and moves the hands to twelve o'clock, whether the clock is fast or slow—in other words, when the hands have been moved beyond twelve o'clock they are returned to twelve, or if they have not reached the figure 12 the hands are moved forward to twelve by the lever F and the heart-cam D. The end of the lever F that engages the heart-cam is heavier than the other end, which latter is engaged by the pin f on the transmitting main wheel B, so that immediately after the end of the lever F is disengaged by the pin the lever is dropped to a fixed stop-pin, g , of the clock-frame, as shown clearly in Figs. 1 and 3.

On the arbor of the minute-hand is arranged a friction-tight pinion, h , which serves for driving said arbor, so as to permit the minute-hand and its arbor to be turned independently of the clock-train when the heart-cam is acted upon by the fulcrumed lever and the actuator on the striking mechanism, said pinion being always in mesh with the time-train, the friction with its arbor C being sufficient to cause said arbor to turn with said pinion by the action of the time-train.

Watch-makers in adjusting the clock-movement compare the same with the normal clock, and instead of passing the movement through a tedious course of adjustment simply set off the difference in time by means of the heart-cam and graduated disk or segment, setting said heart-cam and segment toward one side or the other of the index, according as the clock is faster or slower than the time given by the normal clock.

It is obvious that when the clock is running the difference in time will be mechanically reg-

ulated by the hand-setting lever F when the clock strikes twelve, which moves the heart-cam and sets thereby the hands either forward or backward, so that the normal time is thereby established once in every twenty-four hours. The hands may also be set every twelve hours by arranging on the main wheel B a second pin, f', at a point diametrically opposite to the first pin f, as shown in Figs. 2 and 3. The setting of the hands will only take place while the clock strikes twelve, the adjustment of the hands being then from the figure 12 on the dial either in forward or backward direction, according as the clock runs slower or faster than the normal clock. By this arrangement the work of regulating clock-movements is greatly facilitated, as the small differences of time between the normal time and the movements to be adjusted are accurately determined within twenty-four hours, and then set off on the movements by the proper adjustment of the heart-cams and graduated disks or segments.

Having thus described my invention, I claim as new and desire to secure by Letters Patent—

1. The combination, with a clock mechanism in which the driving-pinion of the minute-arbor is friction-tight on said arbor, of a heart-cam adjustable on said arbor, a lever fulcrumed to the clock-train and adapted to engage said heart-cam at one end, and an actuator connected to the striking mechanism

and engaging the other end of said lever, substantially as set forth.

2. The combination, with a clock mechanism in which the driving-pinion of the minute-arbor is friction-tight on said arbor, of a heart-cam on said arbor, means for adjusting said heart-cam axially on the minute-arbor, a lever fulcrumed to the clock-frame and adapted to engage at one end the heart-cam, and an actuating-pin connected to the striking mechanism and engaging the other end of said lever, substantially as set forth.

3. The combination, with a clock mechanism in which the driving-pinion is friction-tight on said arbor, of a heart-cam on said arbor, a graduated segment attached to said heart-cam and adjustable with the same relatively to a fixed index or pointer on the frame of the clock, a lever fulcrumed to the clock-frame and adapted to engage at one end the heart-cam, and an actuator connected to said striking mechanism and engaging the other end of said lever, substantially as set forth.

In testimony that I claim the foregoing as my invention I have signed my name in presence of two subscribing witnesses.

ALBERT ROSENBAUM.
